UNITED STATES PATENT OFFICE.

JOHN P. CURRY, OF RIVERSIDE, CONNECTICUT.

CONTAINER AND DEVICE FOR OPENING SAME.

Application filed April 15, 1924. Serial No. 706,628.

To all whom it may concern:

Be it known that I, JOHN P. CURRY, a citizen of the United States, and residing at Riverside, in the county of Fairfield and 5 State of Connecticut, have invented certain new and useful Improvements in Containers and Devices for Opening Same, of which the following is a specification.

This invention relates to containers and 10 to devices for opening the same, and more particularly relates to a container provided with special means for facilitating the opening thereof.

Heretofore it has been proposed to open 15 containers and packages by means of a string or tape which has an end exposed on the outside of the package and adapted to be used to tear the paper of the package to facilitate the opening thereof. The necessary projection of the string on the outside of the package prevents the package being made airtight. Also a string cannot be used satisfactorily to tear heavy paper or cardboard. It also requires considerable 20 labor to place the string properly in place on the package.

One of the objects of my invention is to provide a simple, efficient and inexpensive 25 device for opening containers, such as cardboard or paper boxes, cartons, packages, and the like, and to provide such a device which may be associated with the container in such a way that it may nevertheless be hermetically sealed, and a device which is 30 adapted for use with containers of heavy paper, cardboard and the like, as well as of thinner materials.

A further object of my invention is to provide a container provided with special 0 means for facilitating opening thereof, which means may be readily and easily 5 operated, and which may be readily and easily incorporated in the container without interfering with the contained goods 10 and without lessening the capacity of the container.

Another object of my invention is to provide a container provided with special 0 means for facilitating opening, which means are completely enclosed in the container and whereby, when a portion of the container is flexed from the outside the container is pierced from the inside and the 5 ripping open of a portion of the container is facilitated.

Other objects of my invention will be in

part obvious and in part pointed out hereinafter.

In accordance with my invention, I provide an opener which is adapted to be completely enclosed in a container, so as to extend between two opposed portions thereof. The opener has a sufficiently sharp perforating end and is sufficiently rigid, so that it may be moved bodily by flexing a portion of the container inwardly, and when so moved, the perforating end of the opener will puncture and protrude through a portion of the container, permitting this protruding end of the perforator to be grasped by the hand and manipulated to rip or cut the container open, in a neat manner, to the desired extent.

In order that a clearer understanding of my invention may be had, attention is hereby directed to the accompanying drawings, forming a part of this application and illustrating certain possible embodiments of my invention.

Referring to the drawings:

Fig. 1 is a perspective view of a container enclosing an opener of a preferred form, the opener being shown in dotted outline;

Fig. 2 is a view similar to Fig. 1, and shows an end of the opener projected through a portion of the container as a result of flexing one portion thereof toward another portion;

Fig. 3 is a similar view, illustrating one manner in which the opener, after the container has been pierced thereby, may be manipulated to open the container;

Fig. 4 is an elevation of the opener removed from the container;

Fig. 5 is a top view of a container with the wrapping open vertically, and a modified form of opener associated therewith; and

Fig. 6 is an elevation of another modified form of perforator, an associated container being outlined in dot and dash lines.

Similar reference characters refer to similar parts throughout the several views of the drawings.

Referring to the drawings, the container shown in the drawings, for illustrative purposes only, is similar to the extensively used packages which contain twenty cigarettes, and which comprise one or more wrappings of paper and a wrapping of tinfoil folded over at the top of the package and secured in place by a revenue stamp or other label pasted on the package. Sometimes a wrap-

ping of oil paper encloses the package and is hermetically sealed by means of a suitable adhesive.

- Considerable inconvenience is required to 5 open such a package, and it is almost impossible to open the package without using two hands. It is usual to open such a package by tearing off a portion of, or all, the top folds of the wrapping. However, it is 10 difficult to secure a good grip on these top folds to tear open the package. This is especially true of packages having an outer cover of oil-paper or the like, which is hermetically sealed, since all flaps are tightly 15 pasted down. Moreover, the paper is tough and hard to tear.

My invention includes the provision of an opener 1, which is placed in the package 2 immediately below the top folds 3 thereof 20 in such a way that, by flexing inwardly one part, such as 4, of the package, a portion 5 of the opener may be pushed through the opposite part, such as 6, of the package to such an extent that the end 5 of the opener 25 may be grasped readily and easily and the opener manipulated to further cut or rip open the package to the desired extent.

Such opener may comprise a thin, flat sheet-metal member having a pointed end 5. 30 The size and shape of the opener is such that it may be readily and easily completely enclosed in the package when it is packed, thus permitting the package to be hermetically sealed, if desired. For instance, after 35 the cigarettes 7 have been placed in the package, and before the wrappings of the package have been folded down at the top, the opener 1 may be dropped in the package so as to rest flat on the tops of the cigarettes, 40 and then the upper flaps 3 of the package may be brought together in the usual way and the revenue stamp 8 pasted thereover, and, if desired, an outer wrapper of oil-paper may be placed over all this and hermetically sealed. When so placed in a 45 package, the pointed end 5 of the opener and its opposite end 9 are adapted to be so close to the opposite portions 6 and 4 of the package that a person, by pressing these two 50 portions toward each other at or adjacent the opener, may cause the opener to puncture and protrude through a portion of the package, as above stated. The package may be further opened by means of the opener 55 thereafter in many ways. For instance, the end 5 of the opener may be bent upwardly, as shown in Fig. 3. In this case, the sides of the opener will rip open the top of the 60 package along its sides. If desired, however, the opener may be grasped and used in the manner of a paper knife to cut off the top of the package or a portion thereof. After the opener has served its purpose, it 65 may easily be removed from the package by merely sliding it therefrom.

Referring to Fig. 5, the opener may comprise a wire 10 suitably shaped so as to be enclosed in the top of the package and to extend between the two side portions 11 and 12 thereof. One end 13 of the wire is adjacent the wall 12 and the other end 14 is bent into a loop or other suitable configuration and is adjacent the wall 11. The end 13 is preferably sufficiently sharp to cut through the wall 12 easily. By flexing the package 70 to move the portions 11 and 12 toward each other at the location of the opener 10, the opener may readily and easily be pushed through the wall 12 a sufficient distance to 75 permit it to be grasped and to be used to rip open the package.

Another form of opener is illustrated in Fig. 6. In this embodiment of my invention, the opener 15 is elliptical in shape and is formed of wire or a strip of sheet-metal or wood, or the like. Each end 16 and 17 of this elliptical opener is adapted to cut through the package from the inside, so that the package may be opened on either 80 side by pressing against the opener through 85 the package on the opposite side.

It is to be understood that my invention is not limited to cigarette packages, but applies as well to containers of various shapes, sizes and materials, and intended for various commodities. Moreover, the container need not be of thin paper, but may be of thick paper, cardboard or similar material. It is also to be understood that the opener 90 may assume many different shapes and forms, and may be composed of various different materials without departing from the scope of my invention.

What I claim is:—

1. The combination with a container having a wall, of an opener having a perforating end within the container, said end being movable endwise in said container with respect to said wall in such a way as to pierce 100 through said wall from the inside and to protrude therefrom sufficiently to be grasped by a person's fingers.

2. The combination with a container having two opposed portions movable one toward the other, of an opener within the container and extending endwise between said opposed portions and having a perforating end adjacent one of said portions, whereby movement of one of said portions toward 110 the other forces the perforating end of the opener endwise through the adjacent container portion.

3. The combination with a container having two opposed wall portions movable one toward the other, of an opener completely 120 enclosed in the container and having a perforating end directed endwise toward one of said wall portions and having another part adjacent the opposite container wall, whereby movement of one of said opposed wall 125 portions

- portions toward the other forces the perforating end of the opener endwise through the adjacent container wall.
4. The combination with a container having two opposed wall portions movable one toward the other, of an opener completely enclosed within the container and having perforating means disposed adjacent the inside of each of said wall portions, whereby
- 10 said wall portions are pierced from the inside when said wall portions are moved toward each other.

5. The combination with a container having two opposed wall portions one movable toward the other, of an opener completely enclosed within the container and having opposite perforating ends directed against the inside of said opposite wall portions, and each end arranged to pierce the adjacent wall from the inside when said wall portions are moved toward each other.

This specification signed this 11th day of April, 1924.

JOHN P. CURRY.
